REFRIGERANT COMPRESSOR VALVE ARRANGEMENT

Filed Nov. 15, 1943

Fig. 1

UNITED STATES PATENT OFFICE

2,413,653

REFRIGERANT COMPRESSOR VALVE
ARRANGEMENTFrancis I. Rataiczak, Dayton, Ohio, assignor to
General Motors Corporation, Dayton, Ohio, a
corporation of Delaware

Application November 15, 1943, Serial No. 510,315

6 Claims. (CL 62—115)

1

This invention relates to refrigerating apparatus and more particularly to an improved refrigerant compressor valve arrangement for use in a refrigerating system.

This application is directed to an improvement over the arrangement disclosed in my copending application Serial Number 394,645, filed May 28, 1941.

More particularly it is an object of this invention to reduce the amount of labor required in machining the parts of a compressor.

Further objects and advantages of the present invention will be apparent from the following description, reference being had to the accompanying drawing, wherein a preferred form of the present invention is clearly shown.

In the drawing:

Fig. 1 somewhat diagrammatically shows a refrigerating system including a compressor constructed in accordance with my invention;

Fig. 2 is a fragmentary sectional view on an enlarged scale showing the valve assembly.

Referring now to the drawing in which I have shown a preferred embodiment of my invention reference numeral 10 designates generally a hermetically sealed motor compressor unit. Reference numeral 12 designates a substantially cup-shaped stamped sheet metal casing which forms the main support for both the compressor assembly generally designated by the reference numeral 14 and the motor stator 16. Reference numeral 18 designates a conventional motor rotor. A stamped sheet metal end cap 17 encloses the upper end of the cup-shaped casing 12 and forms therewith a high pressure refrigerant vapor chamber. The end cap 17 is welded or otherwise secured to the main casing 12. Heat conducting fins 21 may be secured to the outside of the casing element 12 to help dissipate the heat. The high pressure gas flows through the condenser 20 in which it is condensed and collects in liquid phase in the receiver 22. The liquid refrigerant flows from the receiver 22 into the evaporator 24 through a conventional refrigerant flow control device 26. The refrigerant flow control device may be of any conventional construction and is preferably of the fixed restrictor type in which the high pressure liquid refrigerant is required to flow through a long narrow capillary passage.

The refrigerant vaporized in the evaporator 24 returns to the compressor through the element 28 which communicates with a passage 30 formed in the compressor mounting block 32. The upper end of the passage 30 is provided with an en-

2

larged portion 36 in which a check valve assembly generally designated by the reference numeral 38 is mounted. The check valve assembly 38 comprises a tubular element 40 provided with an internal shoulder which provides a valve seat 42. A valve plate 44 cooperates with the seat 42 in accordance with well-known practice.

A combination valve stop and valve guide member 46 is provided which is formed out of a flat piece of stamped sheet metal material and bent into the shape shown. The element 46 includes three or more pointed projections 48 which serve as stops for limiting the upward movement of the valve plate 44 and also includes a plurality of valve guide members 51 which not only serve to guide the valve plate 44 but also serve to limit the downward movement of the element 46 within the element 40. The outer diameter of the element 40 is slightly less than the diameter of the passage in which it is mounted whereby the element 40 is free to adjust itself within the passage 30. A neoprene gasket 53 is provided as shown and serves to provide a gas tight joint between the outer wall of the element 40 and the wall of the passage 30.

The valve assembly 38 is held in place in the recess 36 by the compressor end plate element 50 which is secured to the block 32 and one or more additional blocks 39, which in turn are welded or otherwise secured to the bottom wall of the casing 12. The bottom surface of the compressor end plate 50 is a lapped surface whereas the top surfaces of the mounting blocks 32 and 39 are merely rough cut surfaces. The term "rough cut surface" as used herein is intended to designate a surface such as produced by the ordinary cutting tool of a lathe as distinguished from a highly polished or lapped surface. It has been found that the blocks 32 and 39 may be used to accurately support the compressor in true perpendicular relationship with respect to the axis of the central opening of the motor stator even though not all of the tool marks have been removed from the upper surface of the mounting blocks.

The upper end surface 57 of the element 40 is a lapped surface which when pressed against the lapped surface on the end plate 50 forms a gas tight seal between the element 40 and end plate 50. The thickness of the gasket 53 is such that when the compressor is fastened onto the mounting blocks 32 and 39 by one or more bolts 56, the surface 57 is held firmly in engagement with the machined surface of the compressor end plate element 50. By virtue of this arrangement it is obvious that the valve assembly 38 is held in

place solely by the compressor end plate 50 whereby in the event of valve failure, the damaged valve part or parts may be replaced with a minimum amount of difficulty.

As shown in Fig. 1 the compressor assembly 14 comprises a lower end plate 50, a cylinder element 52 and an upper end plate 54 which includes the main bearing 56. The compressed refrigerant leaves the compressor 14 through the outlet 10 50 which discharges into the interior of the main motor-compressor casing 12, in accordance with standard practice whereby the pressure surrounding the compressor corresponds to the high side pressure.

The compressor assembly 14 shown in the drawing is intended to represent any conventional rotary compressor having a bottom inlet port such as the port 18. In view of the fact that many of the details of the compressor are immaterial to my present invention, it is not deemed necessary to give a detailed description of the compressor and its mode of operation in this application. For a more detailed description of the compressor construction shown herein reference is hereby made to my aforementioned copending application.

The end plate 50 is provided with a tapered passage 18 which conveys the low pressure refrigerant vapor from the inlet valve assembly to the compression chamber 80. By virtue of the taper in the walls of the passage 18, any slight misalignment between the end plate 50 and the inlet valve 30 will not interfere with the free flow of refrigerant from the inlet valve to the compression chamber.

The mounting block 32 is provided with a refrigerant charging plug 84 which has a first passage 86 communicating with the compressor inlet passage 30 and a second passage 88 communicating with the passage 80 in the mounting block 32. The lower end plate 50 of the compressor is cut away as at 92 so as to provide a passage from the high pressure refrigerant chamber to the passage 80 and the passage 88. The outer ends of the passages 86 and 88 are sealed by means 45 of a plug 94 and a lead plated copper gasket 96. The gasket 96 is provided with apertures 98 in alignment with the passages 86 and 88. The plug 94 is provided with a single passage 100 through which refrigerant and/or lubricant may be added to or removed from the refrigerant system upon partially unscrewing the plug 84. By virtue of this arrangement, both the high side and the low side of the refrigerating system may be very quickly evacuated prior to charging the system with refrigerant and lubricant.

The motor stator 16 is held in place by means of special clamps such as 102. In the prior art devices it has been customary to provide a press fit between the outer shell of the compressor and the motor stator. In such an arrangement, it is very difficult to properly hold the motor stator in place unless a very heavy cast iron frame or the equivalent is used, and once the motor stator is inserted, it is very difficult to remove it for inspection or repair purposes. By virtue of the clamping arrangement shown, a light weight sheet metal casing may be used and the final sizing operation may be performed merely by forcing a die of proper size onto the open end of the casing so as to deform the projecting portion of the clamps 102 the necessary amount. This arrangement of parts and method of sizing eliminates the necessity for turning the inner surface of the outer shell 12 to size on a lathe. The clamping

elements 102 are provided with lugs 108 and 109 which are bent over so as to hold the motor stator in proper position within the casing 12.

The foregoing construction reduces the number of parts required and simplifies the machining operations on the few parts which are required thereby cutting the cost of assembly considerably.

While the form of embodiment of the invention as herein disclosed constitutes a preferred form, it is to be understood that other forms might be adopted, as may come within the scope of the claims which follow.

What is claimed is as follows:

1. In a refrigerating system, a compressor, a casing enclosing said compressor, said compressor having an inlet port in one wall thereof and having a lapped surface adjacent to said inlet port, means for discharging the compressed refrigerant into said casing, a compressor mounting block secured to said casing and having a low pressure refrigerant vapor passage therein communicating with said inlet port, means providing a gastight seal between the passage in said mounting block and said compressor including a tubular insert in said vapor passage having a lapped surface in engagement with the lapped surface on said compressor, and a gasket means between said tubular insert and the wall of said passage, said gasket means serving to urge said tubular insert into sealing engagement with the lapped surface on said compressor.

2. In a sealed motor compressor mechanism, the combination, a casing, a compressor within said casing having a port in one wall thereof, said compressor having a smooth outer surface adjacent said port, a compressor mounting block projecting through one wall of said casing and having a refrigerant passage in alignment with said port, and a valve assembly disposed within said refrigerant passage and held in place therein by the compressor, said valve assembly including means forming a gas tight seal with said smooth surface.

3. In a compressor mechanism, the combination, a casing, a compressor within said casing having a port in one wall thereof, a compressor mounting block projecting through one wall of said casing and having a refrigerant passage in alignment with said port, a valve assembly disposed within said refrigerant passage and held in place therein by the compressor, said compressor and said valve assembly including opposed smooth surfaces, and resilient means holding said opposed surfaces in sealing engagement with one another.

4. In a sealed motor compressor mechanism, the combination, a casing, compressor mounting blocks secured within said casing, a refrigerant passage through one of said blocks, a valve assembly disposed within said passage, resilient means for biasing said valve assembly so as to project beyond the surface of said block, the projecting portion of said valve assembly including a smooth sealing surface, a compressor assembly having an inlet port in alignment with said passage and having a smooth surface in engagement with the smooth surface on said valve assembly.

5. In combination, a casing, a compressor mounting block within said casing, a refrigerant passage in said mounting block, a valve assembly disposed substantially within said passage, a motor stator disposed within said casing having a central opening therein, the upper surface of said mounting block comprising a rough cut surface

arranged at right angles to the axis of said central opening, a compressor assembly disposed within said casing and having a smooth surface resting on said compressor mounting block and having a port communicating with said refrigerant passage, said valve assembly including an element having a smooth surface in sealing engagement with said first named smooth surface, and a motor rotor disposed within said central opening in driving engagement with said compressor.

6. In combination, a compressor, a casing enclosing said compressor, said compressor having a

wall member having a fluid passage therein, a compressor mounting member abutting said wall member and having a fluid passage substantially in alignment with said first named passage, one of said members having a lapped surface adjacent said passage, the other of said members having an enlargement in its fluid passage, a valve assembly disposed within said enlargement comprising a tubular member having a lapped end surface in engagement with said first named lapped surface, and means biasing said lapped surfaces into sealing contact with one another.

FRANCIS I. RATAICZAK.
